COMBUSTION APPARATUS

Clifford S. Cody, Sharon Hill, Pa., assignor to
Westinghouse Electric & Manufacturing Com-
pany, a Corporation of Pennsylvania

Application March 11, 1932. Serial No. 598,254

2 Claims. (Cl. 110—171)

My invention relates to combustion apparatus and more particularly to improvements in water-supply and protecting castings used in conjunction with the walls of refuse and ash pits of 5 stoker-fired furnaces.

In the copending application of Robert A. Foresman, Serial No. 498,929, filed November 29, 1930 and assigned to the Westinghouse Electric and Manufacturing Company, there is described 10 and claimed a cast metal box-like structure which rests upon the upper surface of the front wall of a clinker pit and serves both as a bearing support for the lower end of a stoker grate and as a protection for the upper face of the 15 pit wall. The cast metal structure is provided with a chamber in the interior thereof, into which water from an exterior source is conducted. Openings are provided at the clinker pit side of the structure and provide for the flow 20 of water out of the chamber and onto the inner surface of the clinker pit wall. The present application is in the nature of an improvement over the structure disclosed and claimed in the above-identified application of Foresman.

25 It is an object of this invention to provide apparatus of the character set forth which is improved in construction, is simple, can be manufactured at a low cost, and one which is extremely durable.

30 A further object is to provide a removable cover plate for this type of structure which is at all times positively cooled.

According to a preferred embodiment of my invention, I attain the above objects by providing a hollow cast metal cap which rests upon the upper surface of a clinker pit wall and includes a bottom wall having ribs formed therein which define channels extending transversely of the clinker pit wall; and a front wall having an opening therein adapted to receive a water supply means. The cap includes further a rear wall, the lower end of which defines, in conjunction with the rear end of the bottom wall, an opening extending transversely of the cap for permitting water to flow out of the cap and onto the inner face of the clinker pit wall; side walls 35 joining the front and rear walls; and a top wall inclined downwardly and providing a bearing surface for the lower end of a progressive feed stoker grate; at least the rear portion of the top wall and the front wall being in the form of a removable piece having ribs formed on the under side thereof which define channels extending transversely of the clinker pit wall.

40 Water is admitted to the interior of the cap in

the form of a spray which serves to maintain the inner surface of the metal in a cool condition, and hence protect the metal from the heat. Thorough distribution of the water over the inner surfaces of the cap is insured by the ribs 45 on the bottom wall and those on the top and rear walls. The water flows out of the ends of the grooves and onto the front face of the clinker pit wall in an even sheet, thereby insuring the protection of such face. Also, as the rear portion of the top wall and the front wall are in the form of a removable piece, I provide for the ready replacement of those portions of the structure which are most subjected to the heat of the 50 fire.

These and other objects are effected by my invention as will be apparent from the following description and claims taken in connection with the accompanying drawing, forming a part of 55 this application, in which:

Fig. 1 is a fragmentary, transverse, sectional view showing the lower portion of a progressive feed stoker grate and the upper end of the front wall of the clinker pit with my improvement resting on such wall and supporting the lower 60 end of the grate;

Fig. 2 is a detail view illustrating in elevation the rear face of my improved cap-structure;

Fig. 3 is a transverse sectional view on the line 65 III—III of Fig. 4 and showing my improvement with the cover removed;

Fig. 4 is a view similar to Fig. 2 with the cover removed;

Fig. 5 is an end elevation of the cover; and,

Fig. 6 is a bottom plan of the cover shown in 70 Fig. 5.

Referring now in detail to the construction illustrated in the accompanying drawing, the reference numeral 10 indicates the lower portion 75 of a movable overfeed grate section of a progressive feed stoker of the type disclosed in the application of Foresman No. 498,929 referred to above. The reference numeral 11 indicates the upper end of the front wall of a clinker pit also illustrated in the application of Foresman 80 aforementioned.

Resting on the upper face of the front wall 11 is a hollow cast metal cap structure 12 which comprises a bottom wall 13 engaging the pit wall; a front wall 14 having an opening 15 formed therein through which extends a water supply pipe 16; a rear wall 17 terminating short of the bottom wall 13 to provide an opening 18, through which water flows onto the inner 100 face 19 of the clinker pit wall 11; side walls 20

and 21 joining the front and rear walls; and a wall 22 providing both a top for the cap and a bearing surface for the lower end of the over-feed grate 10.

5 The rear portion of the top wall 22 and the rear wall 17 is in the form of a removable piece 23 which is detachably secured to the remaining portions of the top wall 22. The sides of the piece 23 overlap and rest on the upper and 10 rear edges of the side walls 20 and 21. The piece 23 is provided at the upper end thereof with spaced lugs 24 which fit within openings 25 formed in the top wall 22 and serve to maintain the piece in place on the cap. Lugs 26 and 15 27 extend inwardly from the side walls 20 and 21, respectively, and removable pins 28 and 29, fitting within openings 30 and 31 formed in the removable piece, extend behind the lugs 26 and 27 and serve to aid in maintaining the removable piece in position. It will be readily seen that in order to remove the piece 23, the pins 28 and 29 are first withdrawn and the piece lifted by the rear end and rotated in a counter-clockwise direction as viewed in Fig. 1 until the lugs 24 are disengaged from the openings 25, and then the piece may be bodily lifted out. To 20 replace the piece, the reverse procedure is followed.

30 A nozzle 32 is secured to the inner end of the pipe 16 and serves to provide for the emission of water in the form of a spray which strikes and keeps cool the under face of the top wall 22 and rear wall 17.

35 The upper surface of the bottom wall 13 is provided with ribs 33 which define channels 34 extending from the front wall 14 towards the rear wall 17 and transversely of the pit wall 11 for insuring the distribution of water over the bottom wall and for directing the flow of such water onto the pit wall. A depending flange 35 is provided at the rear edge of the bottom wall and fits within a recess 36 in the pit wall 11. The ribs 33 and channels 34 are continued onto the exposed face of the flange 35.

40 45 The ribs 33 provide for the proper distribution of the water even though the casting may not be in a horizontal position. For example, should there be no ribs and the casting tilted, the water from the spray would tend to flow laterally along the bottom wall 13 to the lowermost side thereof and from there onto the front face of the wall 11. The channels prevent this action by preventing the flow of water from the spray in any direction except toward the clinker pit, thereby assuring the distribution of the water and maintenance of the casting in a cool condition.

50 55 The underside of the removable piece 23 is provided with ribs 38 and 39, the ribs 38 being continuations of the lugs 24. The ribs 38 and 39

60 extend in the same general direction as the ribs 33 and define channels 40 for insuring the distribution of water over the inner surfaces and thereby provide for the positive cooling thereof and for directing the water onto the front face of the clinker pit wall. Water emitting from the spray nozzle necessarily strikes the underside of the piece 23 at angles, and obviously thorough distribution could not be had were it not for the channels defined by the ribs.

65 70 From the above, it will be easily understood that I have provided a cap structure for the front wall of refuse pits which provides for the thorough distribution of water onto the front wall of the clinker pit and for the positive cooling of those portions thereof which are subjected to the heat of the fire.

75 80 While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

85 90 What I claim is:

95 100 1. The combination with a refuse pit wall, of a hollow cast-metal cap for protecting such wall and for supplying a covering of cooling water to the inner face thereof and comprising a bottom wall resting on the refuse pit wall; a front wall; a rear wall terminating short of the bottom wall to define an opening extending for the width of the cap; side walls connecting the front and rear walls; a top wall providing a covering for the 105 cap; the bottom wall having ribs provided on the upper face thereof and defining channels extending from the front wall to the rear wall of the cap; and means providing for the admission of water to the interior of the cap.

110 115 2. The combination with a movable grate structure and a refuse pit wall, of a hollow cast-metal cap supported upon the top surface of the pit wall and providing a bearing support for at least portions of the movable grate; the cap fur-

120 125 130 135 ther providing for the supply of cooling water to the inner face of the pit wall and comprising a bottom wall resting on the refuse pit wall; a front wall; side walls; a rear wall; and a top wall; at least the rear portion of the top wall and the rear wall being in the form of a detachable piece terminating short of the bottom wall to provide an opening extending transversely of the cap; the under surface of said detachable piece being provided with ribs defining channels extending in a direction transverse to the wall of the refuse pit; and means providing for the admission of water to the interior of the cap.
